ROSARY CROSS CASE

Francis X. Menz and Gus C. Menz, Millville, N. J.

Application February 24, 1950, Serial No. 145,932

1 Claim. (Cl. 206—19)

1

This invention relates to jewelry and particularly jewelry used in connection with religious services, and in particular the invention relates to the cross of a rosary wherein the cross is hollow and a cover is removably connected thereto whereby the beads may be stored in the cross.

The purpose of this invention is to form a cross of a rosary whereby the cross may be used as a carrier for the beads.

Various types of cases have been provided as carriers for a rosary, but these are separate and independent elements and with the parts provided as separate units either the rosary or the case may be misplaced. With this thought in mind this invention contemplates a cross in the form of a case in which the beads of the rosary are permanently attached thereto and the cross is so designed that the beads may be stored therein.

The object of this invention is, therefore, to provide means for forming the cross of the rosary whereby the beads thereof may be stored and carried therein.

Another object of the invention is to provide a cross of a rosary that is provided with a removable cover and that is permanently attached to the beads of the rosary.

A further object of the invention is to provide a rosary having a cross in which the cross provides a storage case and carrier for the beads, and in which the device is of a simple and economical construction.

With these and other objects and advantages in view the invention embodies a hollow cross having the beads of the rosary permanently attached to one end thereof and having a cover adapted to be opened for removing and replacing the beads.

Other features and advantages of the invention will appear from the following description taken in connection with the drawing wherein:

Figure 1 is a view illustrating the case forming the cross with the beads of the rosary extended therefrom.

Figure 2 is a view showing the cover of the cross hinged to the end of one of the arms thereof and showing the cover in the open position.

Figure 3 is a view illustrating a modification wherein the body of the cross is provided with a sliding cover and in which the cover is shown in the partly open position.

Referring now to the drawings wherein like reference characters denote corresponding parts the rosary of this invention includes a hollow casing 10, in the form of a cross, a cover 11 and the beads 12 of a rosary.

The upper end of the casing 10 is provided with an opening 13 through which the beads 12 are attached to the end of the cross, as shown in Figure 2, and the cover 11 is pivotally attached to the end of one of the arms by a hinge 14. The

2

opposite end of the cover is provided with a spring latch 15 that snaps over the end of the opposite arm of the cross whereby the cover is secured in the closed position as shown in Figure 1.

5 In the design illustrated in Figure 3 a cross is shown with a hollow stem or body 16 having arms 17 and 18 extended from the sides and the upper edges of the body are provided with beads 19 and 20 over which a cover 21 is slidably mounted as shown. The cover 21 is provided with downwardly extended flanges 22 and 23 with lips 24 and 25, respectively extended inwardly from the lower edges of the flanges whereby the lips are positioned under the beads 19 and 20. 10 In this design the end of the body 16 of the cross is provided with an opening 26 through which the beads 12 of the rosary are attached as shown.

With the parts arranged in this manner the beads of the rosary may be nested in the body of the cross and with the cover closed the beads may be stored therein or carried thereby.

The cross may be formed of any suitable material and the outer surface may be coated or plated, as may be desired.

15 25 It will be understood that modifications may be made in the design and arrangement of the parts without departing from the spirit of the invention.

What is claimed is:

30 In a cross-shaped receptacle, the combination which comprises an elongated substantially hollow body having arms extended therefrom, said arms being box-like and enclosed and the upper surfaces thereof being spaced from the upper 35 surface of said body said body being rectangular shaped in cross section and having a base with sides and ends extended upwardly therefrom and with beads on the outer edges of the sides that extend above the plane of the arms due to the spacing of the upper surface of the arms from the upper surface of the body, a cover having depending flanges at the sides with lips on the edges of the flanges slidably mounted on the upper edges of the sides of the body with the flanges thereof extended over the beads of the said sides, the said arms being spaced from one end of the body, and a rosary attached to the end of the body from which the arms extend whereby with the cover in the open position the rosary is inserted in the said body.
